(57) **CLAIM**

The ornamental design for a garden hose, as shown and described.

DESCRIPTION

FIG. 1 is a front elevational view of a garden hose showing my new design;

FIG. 2 is a perspective view thereof; and,

FIG. 3 is another perspective view thereof.

The garden hose is shown with a dash-dot symbolic break in its length. The appearance of any portion of the garden hose between the break lines forms no part of the claim.
